CIRCUIT CONTROLLING MEANS

William H. Frank and Joseph Messing, Detroit,
Mich., assignors to Bulldog Electric Products
Company, Detroit, Mich., a corporation of
West Virginia

Application November 7, 1934, Serial No. 751,834

24 Claims. (Cl. 200—88)

This application relates to circuit controlling means or circuit breakers and particularly to details of construction thereof, and is a continuation in part of our application Serial No. 697,859, filed November 13, 1933, which application in turn is a division of our application Serial No. 614,362, filed May 31, 1932 which became Patent No. 1,952,040 on March 20, 1934.

The principal object of the present invention is to provide, in a circuit breaker, means whereby the circuit breaker will have a delayed release on a prolonged moderate overload, an instantaneous release immediately upon the arising of an excessive overload, and no release upon a momentary moderate overload. In the embodiment disclosed, this object is attained by providing an instantaneously acting magnetic release means, a delayed acting thermal release means overcontrolling the magnetic means, and a magnetic means for overcontrolling the thermal means, the last mentioned magnetic means operating immediately upon the arising of an excessive overload to overcontrol the thermal means and cause instantaneous release.

A further object of the invention is the provision of an automatic release and reset circuit breaker. In the embodiment disclosed, the circuit breaker is reset automatically after release by the influence of gravity.

A further object is the provision of an automatic release and reset circuit breaker constructed to release after a time interval on a prolonged moderate overload, or instantaneously after the arising of an excessive overload, but holding under momentary moderate overloads.

A still further object is the provision of an automatic release and reset circuit breaker having means for delaying the automatic reset operation.

Still further objects are circuit breakers embodying one or more of the features previously outlined, alone or in combination.

For an understanding of the embodiments here disclosed, reference will be had to the appended drawings. In these drawings,

Fig. 1 shows a circuit breaker of the automatic release and reset type, and having a quick acting magnetic release means, a slow acting thermal release means for overcontrolling the magnetic release means, and a quick acting magnetic overcontrol for the thermal release means;

Fig. 2, shows in combination with the breaker of Fig. 1, a means for delaying automatic reset operation.

Figs. 1a, and 2a show the modifications in open circuit position following automatic thermal release.

In Fig. 1, there is disclosed a circuit breaker employing a solenoid 101 whose plunger 102 is connected through a link 103 to a breaker contact arm 104 by a pin and slot connection at 105. A lug 106 on the link 103 is normally caught under a pivotally mounted cross piece 107, restrained against pivotal movement for release of link 103, by the tip 108 of a thermal holding element 109. Pedestals 110, 111 pivotally support the contact arm 104 and the cross piece 107. A hill and valley spring 112 normally holds contact 104 in position, off or on contacts 114.

The operation of this form of circuit breaker is as follows: When an ordinary or moderate overload occurs, the solenoid 101 is energized and tends to pull arm 104 upwardly to break the circuit. However, unless the overload has endured sufficiently long to warp element 109 to the right and to release cross link 107, the solenoid cannot effect circuit breaking since the link 103 is held down by the cross piece 107. After a predetermined interval of overload, the warping element 109 releases the parts for circuit breaking movement by the solenoid.

It will be seen that due to the pin and slot connection 105, the pull of the solenoid gives the link 103 sufficient momentum before contact arm 104 is urged upwardly to make it certain that the solenoid will positively and quickly effect circuit breaking.

For a heavy overload or short circuit, instantaneous break ought to be provided, and for this purpose we provide quick break means including an armature 116, pivoted at 117, to a pedestal 118. On heavy overload, this armature will be attracted by the solenoid to overcome the action of the spring 119 and force the thermal element 109 to the right and thus allow the circuit breaker to trip instantaneously.

It will be seen that the construction here shown includes parts so arranged that the speed of release will vary with the intensity of the overload, which is a desirable characteristic; and that we provide a belated release for moderate overloads, through thermally responsive means, and an instantaneous release for heavy overloads, through magnetic means. It will also be noted that the same magnet is used for positive break and for the actuation of the instantaneous breaking means, the armature 116.

To reset the breaker, the plunger 102 and with it the link 103 may be moved down manually.

until lug 106 snaps down past the cross piece 107. Or, if desired, reliance may be placed on gravity to move the plunger 102 and link 103 down until lug 106 snaps past cross piece 107, 5 the parts here functioning to reset the breaker automatically.

If it be found that gravity alone is not sufficient to cause automatic reset, as for example, when the breaker is mounted in any position but 10 the one shown, a spring may be utilized to move 10 the plunger 102 out of the solenoid for automatic spring-caused reset. Where the parts are mounted as shown, however, gravity alone may be relied on to cause automatic reset.

15 It will be observed that since, in the breaker of Fig. 1, the automatic reset action takes place before the thermal element 109 cools, the right end of the cross piece 107 is moved upwardly out of the path of the tip 108 of the thermal element 20 before the thermal element returns to its original holding position. This characteristic automatically insures proper timing of the operation 25 of the parts and insures the thermal element functioning as a holding means immediately upon its return without further manipulation on the part of the operator.

The breaker of Fig. 1, which is of the automatic reset type, will reset itself automatically, 30 as soon as the circuit is broken, due to the consequent immediate deenergization of solenoid 101. Under certain circumstances, as where the overload is a continuing one, the breaker will automatically release and reset in cycles, and these 35 will be so frequent that the contacts at 114 will soon burn out, not having time to cool between cycles. For this reason it is contemplated to provide, as an adjunct to the automatic release and reset breaker here shown, means for delaying the automatic reset action so that the cycles 40 of automatic release and reset will not be so frequent, even when the overload is continued. Such means is shown in Fig. 2 in combination with certain cooperating parts of the breaker of Fig. 1, other parts being omitted for purposes of 45 clarity, and such means, to be known as means for delaying automatic reset operation, will now be described.

The cross piece 207 of Fig. 2, replacing the cross piece 107 of Fig. 1, is mounted to reciprocate 50 between rollers 220 mounted on pedestal 111, and is formed with a lug 221 cooperating with the lower end of the pivoted armature 116, whereby the quick acting armature may form a holding means for the cross piece, overcontrolling 55 the delayed action of the thermal element whose tip is received in a groove 222 of the cross piece. The cross piece is formed with a slot 223 formed to cooperate with a latch 224 pivotally mounted on the link 103 and urged by a spring 60 to assume the position shown, with the latch engaging a stop 225 formed on the link 103, the latch, however, being movable, in opposition to the spring, from the position shown, in a counterclockwise direction.

65 The operation of the automatic release and reset circuit breaker, when equipped with the above described means for delaying automatic reset operation, will now be described. On the arising of an overload of sufficient duration or 70 degree, the thermal element 109 will warp to the right, pulling cross piece 207 with it, whereupon the right end of slot 223 will clear the right end of latch 224. Immediately thereafter, link 103 will move up to break the circuit, after which 75 latch 224, which had been moved counterclock-

wise as link 103 moved up, returns to its original position with its lower edge resting upon the upper surface of the cross piece 207. The parts will now be held in circuit breaking position against the influence of the contact arm return 5 spring 226 until thermal element 109 cools and returns to its original position. When this happens, cross piece 207 will be moved to the left and the lower part of latch 224 will clear the slot and link 103 will drop, due to the influence of the 10 return spring 226, after which the latch 224, which had been moved counterclockwise as the link 103 moved down returns to its original position with its upper edge resting under the latch 15 surface of the cross piece 207 as shown in Fig. 2, the circuit being remade automatically. Thus it will be seen that automatic reset is accomplished, but is delayed until after the thermal element 109 has had sufficient time to cool.

It is to be noted that the function of the latch 224 is to prevent strain on the thermal element 20 during movement of the plunger 102. Latch 224 might be omitted and replaced with corresponding projections or lugs on the plunger member 103. However, in this event the thermal element 25 would be strained as the plunger 103 was moved.

One very important consideration of the constructions of this case is the characteristic that 30 the breaker operates with a quick break and quick make switching action. This is accomplished by providing the breaker with a force (the solenoid) tending to open or close the breaker, and a latch (thermal) to prevent the 35 application of such force, the operation being such that when the latch is released the breaker will snap open under the force.

Similarly, the breaker is provided with a force 40 which tends to close the breaker (the spring), and the application of such force is prevented by a latch (the thermal latch) which operates, when released, to permit the force to snap the contacts together for circuit closing.

It will therefore be considered that the 45 constructions of this application possess a common and novel characteristic such as is described in detail in the foregoing.

Now having described the embodiments disclosed herein, reference will be had to the following claims for a determination of the scope 50 of the invention.

What we claim is:

1. Circuit breaker holding and releasing means including magnetically actuated circuit controlled 55 means for causing breaker release, and thermally responsive circuit controlled means for inhibiting the releasing action of the magnetically actuated means, and magnetically actuated circuit controlled means energized on the arising of an excessive circuit abnormality for causing instantaneous release of said thermal means and thereby permitting the first mentioned magnetically actuated circuit controlling means held thereby to cause instantaneous release.

2. Circuit breaker holding and releasing means including magnetically actuated circuit controlled 60 means positively connected to the contact parts of the breaker to cause positive release or break thereof, and thermally responsive circuit controlled means for inhibiting the releasing action of the magnetically actuated means, and magnetically actuated circuit controlled means energized on the arising of an excessive circuit 70 abnormality for causing instantaneous release of

said thermal means and thereby permitting the first mentioned magnetically actuated circuit controlling means held thereby to cause instantaneous release.

5. Circuit breaker holding and releasing means including magnetically actuated circuit controlled means for causing breaker release, and thermally responsive circuit controlled means for inhibiting the releasing action of the magnetically actuated means, the thermally responsive means operating, after a predetermined interval of circuit abnormality to permit the circuit breaker releasing action of the magnetically actuated means, and magnetically actuated circuit controlled means 10 energized on the arising of an excessive circuit abnormality for causing instantaneous release of said thermal means and thereby permitting the first mentioned magnetically actuated circuit controlling means held thereby to cause instantaneous release.

20. Circuit breaker holding and releasing means including magnetically actuated circuit controlled means for causing breaker release, and thermally responsive circuit controlled means for inhibiting the releasing action of the magnetically actuated means, the thermally responsive means operating, after a predetermined interval of circuit abnormality, to permit the circuit breaker releasing action of the magnetically actuated means, and magnetically actuated circuit controlled means 25 operable on the thermally responsive means instantaneously, but only on an excessive circuit abnormality, to remove the inhibiting action of the thermally responsive means and permit the first mentioned magnetically actuated means to cause breaker release.

5. Circuit breaker holding and releasing means including magnetically actuated circuit controlled means for causing breaker release, and delayed-action circuit controlled means for inhibiting the releasing action of the magnetically actuated means, the delayed-action means operating, after a predetermined interval of circuit abnormality, to permit the circuit breaker releasing action of the magnetically actuated means, and magnetically actuated circuit controlled means operable on the delayed-action means instantaneously, but only on an excessive circuit abnormality, to remove the inhibiting action of the delayed-action means and permit the first mentioned magnetically actuated means to cause breaker release.

6. Circuit breaker holding and releasing means including circuit controlled releasing means which acquires a releasing tendency immediately upon the arising of a circuit abnormality, and circuit controlled time delay means for inhibiting the releasing action of the releasing means, the time delay means operating, after a predetermined interval of continued circuit abnormality, to permit releasing action of the releasing means, and circuit controlled means operable instantaneously, on the arising of an excessive circuit abnormality, to remove the inhibiting action of the time delay means and permit instantaneous releasing action by the releasing means.

7. An automatic release and reset circuit breaker having circuit breaker holding and releasing means including magnetically actuated circuit controlled means for causing breaker release, and thermally responsive circuit controlled means for inhibiting the releasing action of the magnetically actuated means, and magnetically actuated circuit controlled means energized on the arising of an excessive circuit abnormality for

causing instantaneous release of said thermal means and thereby permitting the first mentioned magnetically actuated circuit controlling means held thereby to cause instantaneous release, the parts resetting automatically after release.

8. An automatic release and reset circuit breaker having circuit breaker holding and releasing means including magnetically actuated circuit controlled means positively connected to the contact parts of the breaker to insure positive release or break thereof, and thermally responsive circuit controlled means for inhibiting the releasing action of the magnetically actuated releasing means, and magnetically actuated circuit controlled means energized on the arising of an excessive circuit abnormality for causing instantaneous release of said thermal means and thereby permitting the first mentioned magnetically actuated circuit controlling means held thereby to cause instantaneous release, the parts resetting automatically after release.

9. An automatic release and reset circuit breaker having circuit breaker holding and releasing means including magnetically actuated circuit controlled means for causing breaker release, and thermally responsive circuit controlled means for inhibiting the releasing action of the magnetically actuated means, the thermally responsive means operating, after a predetermined interval of circuit abnormality, to permit the circuit breaker releasing action of the magnetically actuated means, and magnetically actuated circuit controlled means energized on the arising of an excessive circuit abnormality for causing instantaneous release of said thermal means and thereby permitting the first mentioned magnetically actuated circuit controlling means held thereby to cause instantaneous release, the parts resetting automatically after release.

10. An automatic release and reset circuit breaker having circuit breaker holding and releasing means including magnetically actuated circuit controlled means positively connected to the contact parts of the breaker to insure positive release or break thereof, and thermally responsive circuit controlled means for inhibiting the releasing action of the magnetically actuated means, and magnetically actuated circuit controlled means energized on the arising of an excessive circuit abnormality for causing instantaneous release of said thermal means and thereby permitting the first mentioned magnetically actuated circuit controlling means held thereby to cause instantaneous release, the parts resetting automatically after release.

11. An automatic release and reset circuit breaker having circuit breaker holding and releasing means including magnetically actuated circuit controlled means for causing breaker release, and delayed-action circuit controlled means for inhibiting the releasing action of the magnetically actuated means, the delayed-action means operating, after a predetermined interval of circuit abnormality, to permit the circuit breaker releasing action of the magnetically actuated means, and magnetically actuated circuit controlled means operable on the delayed-action means instantaneously, but only on an excessive circuit abnormality, to remove the inhibiting action of the delayed-action means and permit the first mentioned magnetically actuated means to cause breaker release, the parts resetting automatically after release.

12. An automatic release and reset circuit breaker having circuit breaker holding and re-

leasing means including circuit controlled releasing means which acquires a releasing tendency immediately upon the arising of a circuit abnormality, and circuit controlled time delay means 5 for inhibiting the releasing action of the releasing means, the time delay means operating, after a predetermined interval of continued circuit abnormality, to permit releasing action of the releasing means, and circuit controlled means operable 10 instantaneously, on the arising of an excessive circuit abnormality, to remove the inhibiting action of the time delay means and permit instantaneous releasing action by the releasing means, the parts resetting automatically after 15 release.

13. In an automatic release and reset circuit breaker, slow acting overload release means and quick acting overload release means, with the latter means overcontrolling the former means, 20 and reset delay means for preventing automatic reset until after a predetermined interval of release.

14. In an automatic release and reset circuit breaker, slow acting overload release means and quick acting overload release means, with the latter means overcontrolling the former means, and reset delay means for preventing automatic reset until after a predetermined interval of release, and controlled by the slow acting release 30 means so as to permit automatic reset when caused so to do by the delayed return of the slow acting release means from release position.

15. In an automatic release and reset circuit breaker, a slow acting overload release latch and quick acting overload release means operable 35 instantaneously on excessive overloads to release the latch, whereupon the quick acting overload release means, normally held against releasing operation by the latch, operates automatically to open the breaker, and reset delay means for preventing automatic reset until after a predetermined interval of release.

16. An automatic release and reset circuit breaker having holding and quick acting overload 45 release and automatic reset means, a holding and delayed action overload release means overcontrolling the quick acting overload release means, and a quick acting overload actuated means overcontrolling the delayed action overload release 50 means, and reset delay means for preventing automatic reset until after a predetermined interval of release.

17. An automatic release and reset circuit breaker having holding and quick acting overload 55 release and automatic reset means, a holding and delayed action overload release means overcontrolling the quick acting overload release means, and a quick acting overload actuated means overcontrolling the delayed action overload 60 release means and reset delay means for preventing automatic reset until after a predetermined interval of release, and controlled by the delayed action overload release means so as to permit automatic reset of the quick acting 65 means when caused so to do by the return of the delayed action overload release means to holding position.

18. An automatic release and reset circuit breaker having holding and delayed action thermally responsive overload release means and a quick acting magnetically actuated overload actuated means overcontrolling the delayed action overload release means, and reset delay means for preventing automatic reset until after 70 a predetermined interval of release.

19. In an automatic release and reset circuit breaker, a slow returning overload release means, automatic reset means, and means preventing automatic reset by the automatic reset means until the slow returning overload release means 5 has returned from release position.

20. An automatic release and reset circuit breaker having circuit breaker holding and releasing means including magnetically actuated circuit controlled means for causing breaker release, and thermally responsive circuit controlled means for inhibiting the releasing action of the magnetically actuated means, and magnetically actuated circuit controlled means energized on the arising of an excessive circuit abnormality 15 for causing instantaneous release of said thermal means and thereby permitting the first mentioned magnetically actuated circuit controlling means held thereby to cause instantaneous release, the parts resetting automatically after release, and reset delay means for preventing automatic reset until after a predetermined interval of release.

21. An automatic release and reset circuit breaker having circuit breaker holding and releasing means including magnetically actuated circuit controlled means for causing breaker release, and thermally responsive circuit controlled means for inhibiting the releasing action of the magnetically actuated means, and magnetically actuated circuit controlled means energized on the arising of an excessive circuit abnormality for causing instantaneous release of said thermal means and thereby permitting the first mentioned magnetically actuated circuit controlling means held thereby to cause the instantaneous release, the parts resetting automatically after release, and reset delay means for preventing automatic reset until after a predetermined interval of release and controlled by the thermal means so as to permit 40 automatic reset when caused so to do by the delayed return of the thermal means from release position.

22. In a circuit interrupter, a movable contact arranged to have a normal tendency to remain in 45 and return to circuit closing position, circuit responsive means arranged to operate, when energized by a circuit abnormality, to move the movable contact to circuit opening position, and when deenergized to permit the movable contact to return to circuit closing position, circuit responsive means normally inhibiting the circuit opening operation of the first means and arranged to operate slowly, when energized by a circuit abnormality, to free the first means so that it may 55 operate for circuit opening, and having a normal tendency to remain in and return to its inhibiting position, and circuit responsive means arranged to operate quickly, when energized by an extraordinary circuit abnormality, to move the second 60 means quickly out of its inhibiting position and thus to free the first means so that it may operate for circuit opening quickly upon the arising of an extraordinary circuit abnormality.

23. In a circuit interrupter, a movable contact 65 arranged to have a normal tendency to remain in and return to circuit closing position, circuit responsive means arranged to operate, when energized by a circuit abnormality, to move the movable contact to circuit opening position, and when deenergized to permit the movable contact to return to circuit closing position, circuit responsive means normally inhibiting the circuit opening operation of the first means and arranged to operate slowly, when energized by a circuit abnormality, to free the first means so that it may 70 operate for circuit opening quickly upon the arising of an extraordinary circuit abnormality.

5 mality, to free the first means so that it may operate for circuit opening, and having a normal tendency to remain in and return to its inhibiting position, and means for delaying the return of the movable contact to circuit closing position following circuit opening movement thereof until the inhibiting means has returned to inhibiting position.

24. In a circuit interrupter, a movable contact 10 arranged to have a normal tendency to remain in and return to circuit closing position, circuit responsive means arranged to operate, when energized by a circuit abnormality, to move the movable contact to circuit opening position, and 15 when deenergized to permit the movable contact to return to circuit closing position, circuit responsive means normally inhibiting the circuit opening operation of the first means and ar-

ranged to operate slowly, when energized by a circuit abnormality, to free the first means so that it may operate for circuit opening, and having a normal tendency to remain in and return to its inhibiting position, and circuit responsive means 5 arranged to operate quickly, when energized by an extraordinary circuit abnormality, to move the second means quickly out of its inhibiting position and thus to free the first means so that it may operate for circuit opening quickly upon the 10 arising of an extraordinary circuit abnormality, and means for delaying the return of the movable contact to circuit closing position following circuit opening movement thereof until the inhibiting means has returned to inhibiting position. 15
